UNITED STATES PATENT OFFICE.

SCOTT H. TOLMAN, OF BOSTON, MASSACHUSETTS.

WELDING-TORCH.

1,141,669.

Specification of Letters Patent. Patented June 1, 1915.

Application filed July 15, 1913. Serial No. 779,159.

To all whom it may concern:

Be it known that I, SCOTT H. TOLMAN, a citizen of the United States, and resident of Boston, in the county of Suffolk and

5 State of Massachusetts, have invented certain new and useful Improvements in Welding-Torches, of which the following is a specification.

This invention relates to welding torches, 10 and it consists in certain features of construction and arrangement, hereinafter explained, whereby leaking at the joints is prevented, flare-backs may be quickly dispelled, and the gases efficiently mixed.

15 Of the accompanying drawings, which illustrate one form in which the invention may be embodied: Figure 1 represents, in section, the head, tip, and mixing means of a welding torch. Fig. 2 represents a side 20 elevation, on a smaller scale, of such a torch. Fig. 3 represents a section of the head alone. Fig. 4 represents a section of the mixing means. Fig. 5 represents an elevation of the rear end of the tip.

25 The same reference characters indicate the same parts wherever they occur.

The torch, as shown by Fig. 2, is intended to be held in the hand of the user, and comprises a handle 10, head 11, tip 12, and 30 gas pipes 13 and 14, all connected according to well-known arrangement.

The head 11 is bored and tapped for the reception of screw-threaded ends of the pipes 13 and 14. The head is also bored to 35 provide a chamber 15, and is tapped as indicated at 16 for the reception of the screw-threaded portion 17 of the tip 12. Passageways 18 and 19 conduct the gases from the pipes 13 and 14 respectively to the mixing 40 means contained in the chamber 15. The mixing means consists in a plug 20 (see Fig. 4), said plug having passageways by which the gases are brought together before they enter the tip. The plug 20 is 45 preferably of such diameter as to fit tightly against the cylindric wall of the chamber 15, so that it is necessary to force the plug into the chamber; and when the plug is driven to the desired position, it fits so 50 tightly as to prevent leaking of gas between its periphery and the wall of the chamber.

The plug 20 has a longitudinal passageway 21 which registers with the passageway 18. The tip 12 has a longitudinal passageway 22 which registers with the pas-

sageway 21 of the plug, the passageways 18, 21 and 22 being, to all intents and purposes, one continuous passageway for the gases.

The head, the plug and the tip are all arranged in abutting end-to-end relation. A gas-tight joint between the abutting portions of the head and plug is effected by providing one of the members with a partially spherical face. In the present instance this face, indicated at 23, is formed upon the plug. The face 23 abuts against the surface 24 of the head and touches the latter only in a circle, the joint being thus limited to circular line contact. The circular contact is coincident with the circumference of the longitudinal passageway. The joint thus effected is less likely to leak than a joint formed by surfaces having considerable contacting area. A similar gas-tight joint is effected between the plug and the tip 12. For this purpose the partially spherical face 25 is preferably, though not necessarily, formed upon the rear end of the tip, and it abuts against the surface 26 at the forward end of the plug.

When the plug and head are assembled, a portion of the chamber 15 in the head is left unoccupied, this unoccupied chamber being indicated at 27 in Fig. 1. The gas from the 35 pipe 14 is delivered into this chamber 27 by the passageway 19 and is conducted from the chamber by inclined passageways 28 formed in the plug. The delivery ends of the passageways 28 are in the longitudinal 40 passageway 21 between the ends of the latter, and they are preferably, though not necessarily, at different distances from the delivery end of the passageway 21. The reason for this offset arrangement is hereinafter explained.

The gases commonly used in a welding torch are acetylene and oxygen, these two gases being conducted separately by the pipes 13 and 14 into the head and therein 100 mixed. The practice hitherto has been to conduct the oxygen to the rear end of the central longitudinal passageway in the head, as at 18, and to admit the acetylene into the longitudinal central passageway between 105 the ends of the latter. I have found in actual practice that flarebacks occur less frequently by reversing this order of admitting the gases, and for this reason I prefer to admit the acetylene through pipe 13 110 and the oxygen through the pipe 14. It has also been customary hitherto to provide the

acetylene supply pipe with a stopcock. I prefer, however, to arrange a stopcock in the oxygen supply pipe, and have shown such a cock at 29 in Fig. 2. This cock is 5 provided with a plunger 30 which may be depressed by the hand grasping the handle 10, to control the passage of oxygen through the pipe 14. It is immaterial whether the cock be open or closed by depressing the 10 plunger, as other valves are customarily provided between the handle 10 and the sources of supply for the gases.

Referring again to the reason for offsetting the delivery ends of the inclined passageways 28, it will be observed that by this arrangement the converging streams of oxygen do not meet in the longitudinal central passageway of the plug. It is well known that two streams which meet spread 15 in the form of a sheet, and consequently if the two streams of oxygen from the passageways 28 were to meet in the center of the passageway 21 they would impede the flow of the acetylene and prevent the desired 20 volume of acetylene from flowing through the tip. According to the illustrated arrangement of the passageways 28, the acetylene becomes mixed first with one stream of oxygen and then the combined gases receive 25 an additional supply of oxygen from the other passageway 28, thus effecting a more perfect mixing of the gases and enabling the desired volume of acetylene to pass through the tip. I believe I am the first 30 to provide a plug for this purpose wherein the gases are brought together and mixed before they reach the delivery end of the plug. I also believe that I am the first to form two abutting members with portions 35 for making a gas-tight joint limited to circular line contact coincident with the periphery of the passageways which conduct 40 the gases.

I claim:

45 1. A welding torch comprising a head, a plug therein and a tip, said plug being between confronting end faces of said head

and tip and having engagement with said faces, said head and tip having interengaging screw threads whereby said tip is 50 brought to bear with force against said plug, said engagement between said head and plug, and said engagement between said plug and tip being limited to circular line engagement, said head, plug and tip having 55 meeting passageways forming one continuous passageway, the circumference of said passageway at the junction of said head and plug coinciding with such circular line of engagement thereof, and the circumference 60 of said passageway at the junction of said plug and tip coinciding with such circular line of engagement thereof.

2. A welding torch comprising a head member and a plurality of other members 65 including a tip member, said members being arranged in a series and in abutting end to end relation, said head member and tip member being the end members of such series and having interengaging screw-threads 70 whereby said tip member may be brought to bear with force against the contiguous intermediate member, each of the abutting end faces of all said members being formed to limit its engagement with the abutting end 75 face of the respective contiguous member to a circular line, said members having longitudinally extending meeting passageways forming one continuous passageway through all said members, the circumference of said 80 continuous passageway being coincident with such circular line of engagement at each of said abutting faces, a plurality of said members having other passageways the delivery end or ends of which join said 85 continuous passageway between abutting end faces of said members.

In testimony whereof I have affixed my signature, in presence of two witnesses.

SCOTT H. TOLMAN.
